Primary Examiner — Dana L Meyrow(74) *Attorney, Agent, or Firm* — Diane E. Furman; Joshua C. Sanders(57) **CLAIM**

The ornamental design for a bottle, as shown and described.

DESCRIPTION

FIG. 1 is a top perspective view of an ornamental design for a bottle according to the present invention;

FIG. 2 is a bottom perspective view thereof;

FIG. 3 is a front elevational view thereof;

FIG. 4 is a rear elevational view thereof;

FIG. 5 is a side elevational view thereof;

FIG. 6 is a side elevational view thereof rotated 180 degrees from FIG. 5;

FIG. 7 is a top plan view thereof; and,

FIG. 8 is a bottom plan view thereof.

The broken lines in FIGS. 1-8 illustrate the portions of the

bottle that form no part of the claim.

1 Claim, 7 Drawing Sheets---
